UNITED STATES PATENT OFFICE.

HARRY W. DENHARD, OF SAN FRANCISCO, CALIFORNIA, ASSIGNOR TO THE CUTLER-HAMMER MFG. CO., OF MILWAUKEE, WISCONSIN, A CORPORATION OF WISCONSIN.

ELECTRIC HEATER.

1,194,343.

Specification of Letters Patent. Patented Aug. 8, 1916.

Application filed October 31, 1911. Serial No. 657,807.

To all whom it may concern:

Be it known that I, HARRY W. DENHARD, a citizen of the United States, residing at San Francisco, in the county of San Francisco and State of California, have invented new and useful Improvements in Electric Heaters, of which the following is a full, clear, concise, and exact description, reference being had to the accompanying drawing, forming a part of this specification.

This invention relates to electric heaters.

It relates particularly to electric heaters adapted for use as electric toasters.

One of the objects of the invention is to provide an improved electric heater.

Another object is to provide an electric heater having improved means for supporting the heating units.

Another object is to provide an improved electric heater which will efficiently radiate the heat developed to the objects to be heated.

Other objects and advantages of the invention will hereinafter appear.

The accompanying drawings illustrate an embodiment of the invention.

The views in the drawings are as follows:

Figure 1 shows a side elevation of a complete heater. Fig. 2 shows an end elevation of the same with one of the doors open. Fig. 3 shows a side elevation of the heating unit with the casing in section. Fig. 4 shows an end elevation of the connections for the unit and the door mechanism, a portion of the casing being removed. Fig. 5 shows a central sectional view on line 5—5 of Fig. 3.

The heater illustrated herein is particularly adapted to be used as an electric toaster, the heating units being supported between vertically extending side members of a substantially U-shaped frame 1 on a base 2, and including a plurality of transversely extending heating coils 3 wound upon insulating tubes 4 having their ends supported in vertically extending terminal inclosing members 5 of a substantially rectangular cross-section which are snugly fitted against the inner surfaces of the side members 1. The coils 3 may, if desired, be formed of a continuous length of high resistance wire, or may be formed of a plurality of lengths of the same. In the construction shown in the drawings, I have illustrated a plurality of coils. The ends 55 of these coils are brought out at each end

through suitable openings 6 in the inclosing members 5. In a preferred form these openings are made by striking up suitable portions 7 and suitable perforations are formed in these struck up portions arranged to receive the ends of wires or rods 8 which pass through the tubular insulating members 4 and have their ends overturned upon the projections 7 as shown in Figs. 3 and 4. As illustrated in these figures, the adjacent openings 6 are provided with struck up portions 7 which extend toward each other.

The resistance wire wound about the tubes 4, is brought out through suitable insulating sheets 9, to conducting plates 10, preferably carrying upon their outer surfaces binding screws 11 to which the ends of the adjacent coils are attached. In this manner a continuous circuit is formed from one of the terminals 12 of the device, through the heating element and back to the opposite terminal 12. The terminals 12 are preferably fixed in suitable openings in the end of the base 2 as shown in Fig. 3 and are suitably insulated therefrom, the ends of the conductors leading to the heating coils passing upward from the inner ends of the same through suitable insulating tubes 13.

As illustrated in Fig. 3, the lower ends 85 of the members 5 are preferably bent over as at 14 and then upward to provide extensions 15 to which the side members 1 may be fixed by suitable screws 16. The upper ends of the members 5 may also be provided 90 with a bent in portion 17 attached to the upper part of the frame. The conductor leading from one of the terminals 12 is led directly to the first heating unit. The conductor from the other terminal extends upwardly along the end member 5 and between the same and the frame 1. The conductor is suitably insulated from the casing by one or more sections of tubular insulating material 18.

In order that the heat may not pass upward from the heating coils too readily so that a proper amount of heat will be given to the articles to be heated, I preferably provide each of the heating coils with a hood or cover 19 of a substantially triangular cross-section, as shown in Fig. 5. In a preferred form the ends of the hood members are attached to the vertically extending end members 5. If desired, the hood members may 110

be of such a length that they will fit snugly between these members 5 or the ends of the hood member 19 may be provided with extensions which pass through the sides of the members 5. In the construction shown each of the hood members 19 is provided with one or more extensions 20 between its ends, on opposite sides of the same, in order to more effectually prevent any contact with the 10 heating wire.

As illustrated in Figs. 3 and 5, the members 1 are connected by a transversely extending bottom member 21. This member is provided with studs 22 on its ends which 15 pass through openings in the lower ends of the members 5 and serve to position the member 21. The member 21 is also provided with one or more transverse extensions 23, and intermediate these extensions is provided with smaller studs 24 arranged to receive the lower ends of the grid rods 25, the upper ends of which are fixed in the frame 1. As shown in Fig. 5 the extensions 23 project 20 on opposite sides of the member 21 in a plane substantially parallel with the base so 25 that they serve to prevent articles held against the grid from sliding down into contact with the base.

The base member 2 is preferably provided 30 with brackets 26, having ears 27 in which are journaled suitable doors 28. The brackets 26 are preferably provided with extensions 29 secured to the top of the base by means 35 of screws 30. The doors 28 are preferably 40 so constructed as to snugly inclose the heating unit, as shown in Figs. 1 and 2. In a preferred form they are provided with side flaps 31 which pass along each side of the end members 1 and are limited in their forward movement by suitable pins 32.

In order that the doors may be readily operated, they are provided with a spring mechanism. This mechanism is preferably carried upon the inside of the base 2, beneath the heating element, and preferably 45 consists of a single spring member 33 having one or more spiral turns 34 near its opposite ends, and upwardly extending free ends 35, passing through openings or perforations 36 in the bottom of the doors, and bent over as at 37 within the ends of the same. When 50 it is desired to close the doors, all that is necessary to do is to start the door in its movement whereupon the spring completes 55 the movement of the same. Further, the spring tends to hold the doors snugly closed, and thus prevents accidental opening of the same. In a preferred form the doors are also provided with a chamber 38 formed between the inner and outer walls which serves 60 to cut down the heat losses at the side of the heater. It is of course obvious that the doors may be provided with any suitable handle or knob, such as the wire-wound knob 65 39 shown in Figs. 1, 2 and 5. A handle 40

may be provided upon a top plate 41 carried by the frame 1, so that the heater may be readily moved from place to place as desired. It is also obvious that the base 2 may be suitably insulated as by mounting the 70 same upon suitable feet 42, preferably provided with insulating pads 43.

By my improved construction I have provided a heater of increased efficiency where-in the heat developed by the passage of current through the heating coils is radiated to the objects to be heated. Such a device is particularly adapted to use in connection with electric heaters of the type known as electric toasters, broilers or the like. The 80 losses of heat by the upward radiation of the same and its conduction to the inclosing casing are effectually prevented by my improved construction. By my improved arrangement of doors, I have been able to provide a door mechanism which may be readily operated and is extremely convenient in use. Further, by the arrangement of the heat insulating chamber between the walls of the door, I have materially cut down the heat 85 loss by radiation from the doors, and have thus more effectually concentrated the heat around the objects to be heated.

By my improved construction and arrangement I am able to provide an exceedingly 90 large surface of resistance material and utilize practically this entire surface in heating the articles. Further, by my improved manner of mounting and insulating the resistance material, I have effectually 100 done away with any danger of short-circuiting or the like, and have provided a device which is well adapted to be heated to high temperature. Further, by the improved 105 mechanical construction of the frame and the supports for the heating coils, I have provided a device which is very rugged and well adapted to withstand long use in service.

While I have in this application described 110 for purposes of illustration one form which my invention may assume in practice, my invention is capable of assuming other forms and I consequently do not wish to be limited to this particular form, but wish rather to 115 include all those forms and adaptations of my invention falling within its spirit.

What I claim as new and desire to secure by Letters Patent is:—

1. An electric heater having a plurality of 120 horizontally disposed heat radiating units arranged in substantially the same vertical plane, a supporting frame therefor having struck-up portions to which said units are attached, and hoods above each of said units 125 to reduce the heat loss in an upward direction.

2. An electric heater having a plurality of heating units arranged in substantially the same plane comprising insulated rods wound 130

- with resistance material, a supporting frame therefor having struck-up portions to which said heating units are attached, said resistance material having its ends extending 5 through the openings formed by said struck-up portions, and binder plates located between said struck-up portions and insulated from said frame whereby said units may be connected together electrically.
- 10 3. An electric heater having a plurality of horizontally disposed heating units arranged in substantially the same plane, a supporting frame therefor having struck-up portions to which said units are attached, 15 insulating strips between certain of said struck-up portions, and binder plates on said insulating strips whereby the heating units may be electrically connected.
4. An electric heater comprising a plurality 20 of heat radiating units arranged in substantially the same plane, a supporting frame therefor, guards on opposite sides of said heating units arranged substantially at right angles thereto for confining the heat 25 to the inclosure thus formed and a hood for each of said units to reduce the heat loss in an upwardly direction.
5. An electric heater having a plurality 30 of heating units, a supporting frame therefor having struck-up portions to which said units are attached, said struck-up portions being formed so that openings are provided in the frame through which the ends of the resistance material of the heating units may 35 pass to the outside of the frame.
6. An electric heater having a plurality of heating units, a supporting frame therefor having struck-up portions to which said units are attached, said struck-up portions 40 being formed so that openings are provided in the frame through which the ends of the resistance material of the heating units may pass to the outside of the frame, and insulated means on the outside of said frame 45 adjacent the struck-up portions to which means the resistance material is electrically connected whereby the heating units are connected together.
7. An electric heater having a plurality 50 of heater units arranged in substantially the same plane, a supporting frame therefor having its ends and bottom arranged to confine the heat adjacent the heating units, hoods above each of the units to reduce the 55 heat loss in an upward direction, and heat insulated doors adapted to cover the sides of the frame.
8. An electric heater having a supporting
- frame carrying a plurality of heater units arranged in substantially the same vertical 60 plane, hoods above each of said units for reducing the heat loss in an upward direction, and a door on each side of said heater units, said doors having spaced walls forming heat insulating chambers to reduce the 65 heat loss in a horizontal direction.
9. An electric toaster comprising a frame carrying a plurality of heater units arranged in substantially the same vertical 70 plane, rods adjacent the sides of said units against which the material to be toasted may bear, a hood above each heater unit for reducing heat loss in an upward direction and pivoted doors adapted to hold the material to be toasted against said rods, said 75 doors having spaced walls to reduce heat loss at the sides of the heater units.
10. An electric toaster comprising a frame having vertical end members provided with struck-up portions, heater units carried by 80 said struck-up portions, said portions being formed so that openings are provided in the end members through which the resistance material of the heater units may pass to the outside of said members, insulated binder- 85 plates on the outside of said frame adjacent said openings to which plates the resistance material of the heater units is electrically connected whereby the units may be connected together, and electric terminals connected 90 to certain of said binder-plates.
11. An electric toaster comprising a frame having vertical end members provided with struck-up portions, heater units carried by 95 said struck-up portions, said portions being formed so that openings are provided in the end members through which the resistance material of the heater units may pass to the outside of said members, hoods above each of said units to reduce heat loss in an up- 100 ward direction, said end members being adapted to prevent heat loss at the ends of the units, rods adjacent the sides of the units against which the material to be toasted may bear, and pivoted doors adapted to 105 hold the material to be toasted against said rods, said doors having spaced walls to reduce heat loss in a horizontal direction.
- In witness whereof, I have hereunto subscribed my name in the presence of two witnesses. 110
